FLOAT-OPERATED SWITCH

Charles N. Reavis, Raleigh, N. C., assignor of
two-thirds to Silas B. Coley, Raleigh, N. C.;
Charlotte L. Reavis administratrix of Charles
N. Reavis, deceased

Application February 3, 1945, Serial No. 575,950

1 Claim. (Cl. 200—84)

1
This invention relates to float-operated switches, particularly adapted for use in connection with engine protective systems of the kind disclosed in my copending application for U. S. Letters Patent, Serial No. 568,125, filed December 14, 1944, now Patent No. 2,428,095, issued Sept. 30, 1947, although capable of general use.

The primary object of the present invention is to provide a float-operated switch which is simple in construction, economical to manufacture, and efficient in operation.

Broadly stated, the invention contemplates the provision of a float-operated switch embodying a circuit maker and breaker that includes a fixed contact and a movable contact, said movable contact being movable to a position in engagement with the fixed contact and to a position out of engagement with the fixed contact and being tensioned to normally occupy one of said positions, said movable contact carrying an armature, an arm carrying a permanent magnet and movable to bring the field of its magnet within range of the armature so as to move the movable contact to the other of said positions, or to remove the field of said magnet out of range of said armature so that the movable contact may return to the one position, and a float for moving the arm so as to bring the field of its magnet within the range of said armature or out of range of the latter.

A more specific object of the invention is to provide a float-operated switch embodying a normally closed circuit maker and breaker and a normally open circuit maker and breaker, a vertically movable float, and magnetic means movable by said float for opening the normally closed circuit maker and breaker when the float is in a predetermined raised position and for closing said normally open circuit maker and breaker when the float approaches its lower limit of movement.

More specific objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a substantially central vertical sectional view of a switch constructed in accordance with the present invention.

Figure 2 is a transverse section taken substantially on line 2—2 of Figure 1.

2
Figure 3 is a fragmentary view somewhat similar to Figure 1, but showing the parts in a different position and a different one of the two circuit makers and breakers forming part of the switch shown in Figure 1.

In the embodiment shown, the casing 5a has a bottom water inlet 9 and a top vent 10, and it is divided by a vertical partition 6a into a relatively large water compartment 7a and a relatively small compartment 8a. Mounted in the compartment 8a and upon the partition 6a are circuit makers and breakers 23 and 23'. Also, the compartment 8a is closed by a cover 31a.

Journalized in suitable brackets 34 carried by partition 6a is a horizontal shaft 35 having one end of a float arm 36 fixed thereon. A suitable float 37 is secured on the other or free end of the arm 36. Rigid with and projecting upwardly and downwardly from the arm 36 adjacent the shaft 35 are arms 18a and 18b, respectively. A permanent magnet 19a is carried by the free end of arm 18a, and a similar magnet 19b is carried by the free end of the arm 18b. The arrangement is such that when the float 37 is in its upper limit of movement, the magnet 19a of arm 18a will be moved toward the partition 6a until its field is brought within range of the armature of circuit maker and breaker 23 so as to cause the latter to assume circuit opening condition. When this takes place, the magnet 19b will have been moved so that its field is out of range of the armature of circuit maker and breaker 23', thereby allowing the latter to assume its normally open condition. As soon as float 37 lowers a slight extent, the magnet 19a will assume a position wherein its field is out of range of the armature of circuit maker and breaker 23, thereby allowing the latter to close. Upon continued downward movement of the float 37 until it approaches its lower limit of movement, the magnet 19b will be moved to a position wherein its field is brought within range of the armature of circuit maker and breaker 23', thereby causing the latter to assume circuit-closing condition. Both circuit makers and breakers will be open when the float is in its upper limit of movement, while the circuit maker and breaker 23 will be allowed to close when the float 37 lowers to a slight extent and the circuit maker and breaker 23' will be caused to close when the float 37 completely lowers, the circuit maker and breaker 23 remaining closed when the latter takes place. Thus, the circuit maker and breaker 23 may be used to control the circuit of a warning signal or light, while the circuit maker and breaker 23' will be used to control the circuit of another warning signal or light.

may be used to control grounding of an engine distributor, the closing of the circuit of the signal light being effected before the level of the water lowers to a dangerous point, and the grounding of the distributor to render the engine inoperative taking place when the water has lowered to a dangerous point.

From the foregoing description, it is believed that the construction and operation, as well as the advantages of the present invention will be readily understood and appreciated by those skilled in the art. Also, it will be apparent that the invention may be embodied in forms other than those specifically disclosed, and that changes may be made in details of construction illustrated and described, such as fall within the spirit and scope of the invention as claimed.

What I claim is:

A float-operated switch comprising a casing provided with non-communicating float and contact chambers, said float chamber having a bottom water inlet and a top vent, a normally closed circuit maker and breaker in said contact chamber having a fixed contact and a flexible contact carrying an armature and normally tensioned to engage the fixed contact, a second circuit maker and breaker in said contact chamber including a fixed contact and a flexible contact normally tensioned to disengage from the associated fixed contact and carrying an armature, and actuating means for said flexible contacts

10
15

4
mounted in the float chamber and including a rock shaft, arms projecting upwardly from and downwardly from said rock shaft respectively, permanent magnets carried by the free ends of said arms, a float arm rigid with said shaft and carrying a float, the upwardly extending arm being arranged so that its magnet is moved to bring its field within range of the armature of the first circuit maker and breaker when the float is raised, said downwardly extending arm being arranged so that the field of its magnet is brought within range of the armature of the second-named circuit maker and breaker when the float is lowered.
